UNITED STATES PATENT OFFICE.

WILLIAM T. SMITH, OF ROGERSVILLE, MISSOURI.

MAIL-BAG-RECEIVING APPARATUS.

1,242,381.

Specification of Letters Patent.

Patented Oct. 9, 1917.

Application filed August 4, 1914. Serial No. 855,025.

To all whom it may concern:

Be it known that I, WILLIAM T. SMITH, a citizen of the United States, residing at Rogersville, in the county of Webster and State of Missouri, have invented certain new and useful Improvements in Mail-Bag-Receiving Apparatus, of which the following is a specification.

My invention relates to devices for transferring mail.

The primary object of the invention is to provide an improved, simplified and efficient receiving means so arranged relatively to the delivery means as to positively and safely transfer mail from a stationary support to a fast moving train or vice versa.

A further object of the invention is to so mount the receiving means as to provide for bodily movement thereof into and out of operative position, the normal inoperative position being upon the interior of the mail car at one side of the car door, and the operative position being directly within the door and projected therethrough into the path of the mail to be transferred.

A still further object of the invention resides in the provision of means operating in conjunction with the receiving means for positively and automatically locking the mail in proper place during a transfer thereof, said lock means, if desired, being independently actuatable to provide for a removal of the mail as occasion may demand.

The above and additional objects are accomplished by such means as are illustrated in their preferred embodiment in the accompanying drawings, described in the following specification and then more particularly pointed out in the claims which are appended hereto and form a part of this application.

In describing my invention in detail reference will be had to the accompanying drawings wherein like characters denote like or corresponding parts throughout the several views, and in which:

Figure 1 is a top plan view of the receiving means, the same being shown in an inoperative position with a portion of its support and the mail car in which it is arranged being shown in section;

Fig. 2 is a similar view, the receiving means being shown in an operative position;

Fig. 3 is a side elevation of the device, the same being in an inoperative position; 55

Fig. 4 is a similar view, the device being in an operative position;

Fig. 5 is an enlarged plan view of the receiving means, the casing forming a part thereof being shown in section; 60

Fig. 6 is a longitudinal sectional view taken through the casing of the said receiving means;

Fig. 7 is an edge view of the lazy-tong mechanism forming a part of the receiving 65 means;

Fig. 8 is a plan view of the device as shown in Fig. 7;

Fig. 9 is a detail view of the locking means; and 70

Fig. 10 is a view similar to Fig. 2, the receiving means being disposed at an inclination or angle in order that the lazy-tong mechanism may operate automatically.

Referring now to the drawings by numerals, 1 designates a railway mail car, having the usual door or opening 2 formed in the side thereof. Permanently fastened in any suitable manner, preferably as indicated at 3, to the car interior at a point adjacent 80 the door 2 is the support means for the receiving apparatus designated as an entirety by the numeral 4. The said support means in its preferred embodiment consists of brackets 5 secured as at 3, the brackets supporting a sleeve-like or tubular member 6 closed at one end and open at the other, the latter, or open end being flush with the side of the door 2 adjacent which it is arranged. The member 6 is longitudinally slotted as 90 indicated at 7, one terminal of the said slot 7 being branched at an angle as indicated at 8. Within the tubular member 6 is fitted an arm or support 9 with which is associated a stop element 10 disposed to extend through 95 the slot 7 to limit both longitudinal movement of the support and, when within branch slot 8, to limit movement of the support when turned. When in the latter position, (the stop element being now under 100 discussion), that is, in engagement with the terminal of the slot 8, support 9 is so positioned relatively to the car door 2 as to project the receiving means 4 therethrough and to dispose the said means in a substantially horizontal plane. When in the for-

mer position, that is, with the stop element 8 in engagement with the inner end of slot 7, the receiving means is disposed in a substantially vertical plane and is entirely 5 closed within the car interior, as shown in Fig. 3, at one side of the car door. To permit of bodily adjustment of the member 6, it is but necessary that thumb screws 11 be loosened, said screws being carried by 10 the respective brackets 5.

Passing on to the description of the receiving means, 12 designates a top plate and 13 the base plate, the said two plates with the connecting elements 13' which maintain the plates in spaced relation forming a casing within which the operating mechanism is arranged. Said mechanism is quite simple in its nature and consists of a pair of meshing segments designated respectively 14 and 15, the same being mounted on shafts 16 and 17 extending from one to the other of the plates. An inner casing or housing 18 is arranged to inclose the segments, said housing 18 being suitably 20 grooved to provide for the arrangement of ball bearings 19 upon which segments 14 and 15 rest. Arm 9 is made fast to the receiving means as indicated at 20 and shown to advantage in Fig. 6.

30 Each segment has made fast thereto or integral therewith one of the master links 21 forming a part of suitable lazy-tong mechanism designated as an entirety by the numeral 22, the latter, when the device 35 is in an operative position, being projected through the car door and in the path of the mail to be transferred. The forward outer link of the mechanism 22 has been designated 23 as the said link is cut away as 40 indicated at 24, the recess formed thereby being adapted to receive and retain as will hereinafter fully appear the mail. An extension 25 is made integral with the other outer link of the said lazy-tong mechanism, 45 the said extension being curved forwardly as shown. Pivoted to the extension 25 as indicated at 26 is a retaining element 27 curved to form, in its normal position, a continuation of the extension and, with the 50 extension, acts as a retaining means or locking means whereby the mail subsequent to transfer, is held in place against the link 23 and within the recess 24 above referred to. An eccentric or cam lever 28 is mounted on 55 extension 25, the lever being provided with a lip or flange 29 adapted for engagement with a lug 30 depending from an arm 31 made integral with the retaining element 27 and extending over the extension 25 as 60 shown to advantage in Fig. 8. When lever 28 is swung into a position whereby to engage flange 29 with the lug 30, it is apparent that retaining element 27 is locked immovable relatively to extension 25, thus 65 making it impossible to move the said ele-

ment except through manipulation of the lever. The lever, when swung into the position indicated in Fig. 9, that is, out of engagement with the lug 30 of arm 31, will permit element 27 to swing upon its pivot 70 26 or away from the extension, out of circumferential alinement therewith, said element, when thus positioned, permitting a removal of the mail as occasion may demand. 75

One of the segments, preferably 14, has associated therewith an operating handle 32, the latter being actuatable to operate the lazy-tong mechanism when the device or apparatus is operated by hand. To facilitate movement of the said receiving means into and out of operative position, I provide a handle 33 secured as shown to the casing within which the segments are arranged. 80

In operation, the lazy-tong mechanism is extended as shown in Fig. 10 of the drawings and disposed at an angle so as to extend forwardly or in the direction of travel of the car, so that the mail bag may be received against the link 23. When the impact has occurred the lever 32 is oscillated manually to fold the lazy-tong mechanism whereby the retaining element 27 is quickly embraced about the mail bag and the bag held in the inclosure defined by said retaining element 27, and the recessed portion of the link 23. 90

From the foregoing, taken in connection with the accompanying drawings it will be noted that the mail is grasped and drawn into the car interior with one and the same movement of the receiving means; that the said mail may be quickly removed when within the car interior through manipulation of cam lever 28; and that when not in use, the receiving means may be folded 105 and inclosed entirely within the car and disposed at one side thereof out of the way as shown to advantage in Figs. 1 and 3.

In reduction to practice, I have found that the form of my invention, illustrated in the drawings, and referred to in the above description, as the preferred embodiment, is the most efficient and practical; yet realizing that the conditions concurrent with the adoption of my device will necessarily 110 vary, I desire to emphasize the fact that various minor changes in details of construction, proportion and arrangement of parts may be resorted to, when required, without sacrificing any of the advantages 120 of my invention, as defined in the appended claims.

Having thus fully described my invention, what I claim as new and desire to secure by Letters Patent, is:—

1. A mail bag receiving apparatus including a suitable support, receiving means movable relatively to said support either into or out of operative position, the said receiving means consisting of a casing, lazy- 125

130

tong mechanism movable relatively to the casing, and retaining means mounted on and operable through movement of said lazy-tong mechanism, as and for the purpose set forth.

2. A mail bag receiving apparatus including a suitable casing, lazy-tong mechanism movable relatively to the casing, means actuatable to operate said lazy-tong mechanism, and retaining means mounted on said mechanism, said retaining means being operable automatically through movement of said mechanism, as and for the purpose set forth.

3. A mail receiving apparatus including suitable support means, a casing mounted on said support, segments operating within the casing, lazy-tong mechanism actuatable through movement of said segments, and retaining means mounted on said lazy-tong mechanism, said retaining means operating automatically through movement of said mechanism, as and for the purpose set forth.

4. A mail receiving apparatus including suitable support means, a casing mounted on said support, said casing being movable into and out of operative position, lazy-tong mechanism movable relatively to the said casing, means actuatable to move the said mechanism, the outermost link of the said lazy-tong mechanism when in its projected position being directly engageable with the mail matter to be transferred, and retaining means mounted on said mechanism, said retaining means operating automatically through movement of said mechanism to grasp and hold the said mail matter against said link, as and for the purpose set forth.

5. A mail receiving apparatus including lazy-tong mechanism, the outermost link of the said mechanism being directly engageable with the mail matter to be transferred, means actuatable to operate said mechanism, and means mounted on said mechanism engaging said outermost link, said means operating automatically through movement of said mechanism to grasp and retain the mail matter in engagement with said link in a transferring operation, as and for the purpose set forth.

6. A mail receiving apparatus including suitable lazy-tong mechanism, means actu-

atable to operate said mechanism, the outermost link of the said mechanism when projected being directly engageable with the mail matter to be transferred, retaining means mounted on said mechanism, said retaining means operating automatically to grasp and hold the mail matter against the said outermost link as the lazy-tong mechanism is folded, and means operable independently of the said lazy-tong mechanism to release the mail matter subsequent to transfer, as and for the purpose set forth.

7. A mail receiving apparatus including suitable lazy-tong mechanism, meshing segments actuatable to operate said segments, the outermost link of the said mechanism being directly engageable with the mail matter transferred in the projected position of said mechanism, retaining means mounted on said mechanism adjacent said link, said retaining means operating automatically to grasp and hold said mail matter against the said link as the mechanism is operated in a transferring operation, and means mounted on said retaining means, said last mentioned means being operable independently of said retaining means to release the mail matter subsequent to transfer, as and for the purpose set forth.

8. A mail receiving apparatus including suitable lazy-tong mechanism, means actuatable to operate said mechanism, retaining means mounted on said mechanism, said retaining means operating automatically to grasp and hold the mail matter as the lazy-tong mechanism is actuated, fastening means mounted on said retaining means for holding the latter in operative relation relatively to the lazy-tong mechanism, said fastening means being independently actuatable to release said retaining means to provide for a removal of the mail matter subsequent to transfer, as and for the purpose set forth.

In testimony whereof I affix my signature in presence of two witnesses.
